STOCKING

Curt Seifart, Charlotte, and Avery D. May, Shelby, N.C., assignors to Hudson Hosiery Company, Charlotte, N.C., a corporation of North Carolina

Filed May 13, 1964, Ser. No. 79,965

Term of patent 14 years

(Cl. D47—7)

FIG. 2

FIG. 1 is a schematic view of a stocking; and
FIG. 2 is a substantial scale-wise section of the fabric forming the body of the stocking of our new design.
The welt, toe and heel reinforcements are of conventional plain knit fabric.

We claim:

The ornamental design for a stocking, as shown and described.
